PICTURE FRAME MOULDING

Johnannes Vihma, Toronto, Ontario, Canada, assignor to Artistic Woodwork Co. Ltd., Downsview, Ontario,
Canada

Filed July 22, 1974, Ser. No. 490,263

Term of patent 14 years

Int. Cl. D6—07

U.S. Cl. D6—246

The figure is a perspective view of a picture frame moulding showing my new design, a portion thereof being broken away to indicate indeterminate length.

I claim:

The ornamental design for a picture frame moulding, as shown and described.
